(57) CLAIM

I claim the ornamental design for a pair of soft skull slippers, as shown and described.

DESCRIPTION

FIG. 1 is a rear, top and side perspective view of one soft skull slipper embodying the design of the present invention, the other slipper being identical to the slipper shown herein.

FIG. 2 is a top plan view thereof.

FIG. 3 is a side elevational view thereof, the side opposite being identical to the side shown in FIG. 3.

FIG. 4 is a front elevational view thereof.

FIG. 5 is a rear elevational view thereof; and,

FIG. 6 is a bottom plan view thereof.
